Primary Examiner — R. Johnson(74) Attorney, Agent, or Firm — Reilly Intellectual Property Law Firm(57) CLAIM

The ornamental design for a guitar pick holder as shown and described.

DESCRIPTION

FIG. 1 is a front perspective view of a guitar pick holder, showing the first embodiment of my new design;

FIG. 2 is a rear perspective view of FIG. 1;

FIG. 3 is a top plan view of FIG. 1;

FIG. 4 is a front view of FIG. 1;

FIG. 5 is a bottom view of FIG. 1;

FIG. 6 is a side view of FIG. 1;

FIG. 7 is an opposite side view of FIG. 6;

FIG. 8 is a front perspective view of a guitar pick holder, showing the second embodiment of my new design;

FIG. 9 is a rear perspective view of FIG. 8;

FIG. 10 is a top plan view of FIG. 8;

FIG. 11 is a front view of FIG. 8;

FIG. 12 is a bottom view of FIG. 8;

FIG. 13 is a side view of FIG. 8; and,

FIG. 14 is an opposite side view of FIG. 13.

The broken line portion of FIGS. 2, 5, 9 and 12 is included to show environment that forms no part of the claimed design.
